RAILWAY CAR

Cyrus Hankins, Washington, D. C.

Application January 16, 1936, Serial No. 59,458

14 Claims. (CL 105—282)

My invention relates to railway freight cars of the type employed for transporting in bulk finely divided material and more particularly it relates to the discharge door mechanisms of such cars.

Cars of this type are customarily provided with sliding doors for closing the openings through which the finely divided material is adapted to discharge by gravity and the principal object of this invention is to provide such doors with means whereby they may be easily operated.

A primary feature of the invention consists in associating with the door slidable means having wedging engagement therewith for raising the door upwardly toward the plane of the lading discharge opening so as to cause it to occupy an elevated position when closed.

Another feature of the invention consists in providing means for supporting the sliding door in an elevated position when the latter is closed, said means being initially movable independently of the door to enable the latter to move downwardly and being thereafter movable to slide the door toward open position.

A further feature of the invention consists in associating with the discharge opening of the car two slidable plate-like members, one of which constitutes a door for closing the opening and the other of which constitutes means for raising the door upwardly toward the plane of the lading discharge opening to cause it to occupy an elevated position when closed.

A still further feature of the invention consists in providing the means for supporting the door in an elevated position, when the latter is closed, with a portion affording a seat for a removable lever whereby said means may be easily actuated to permit the door to move downwardly away from the plane of the lading discharge opening.

Other features of the invention, residing in advantageous forms, combinations and relations of parts, will hereinafter appear and be pointed out in the claims.

In the drawings:

Figure 1 is a horizontal sectional view through the lower portion of a hopper of a railway car, the door mechanism being shown in plan.

Figure 2 is a vertical sectional view taken on line 2—2 of Figure 1.

Figure 3 is a vertical sectional view similar to Figure 2, the parts of the mechanism being shown in the positions they occupy after the door has moved downwardly away from the plane of the lading discharge opening and is ready to be moved toward open position.

Figure 4 is a fragmentary vertical sectional

view illustrating the relative position of the parts after the door has been moved to open position.

Figure 5 is a vertical sectional view taken on line 5—5 of Figure 2.

Figure 6 is a vertical sectional view taken on line 6—6 of Figure 2.

Figure 7 is a front end view of the top plate-like member of the door mechanism.

Figure 8 is a fragmentary plan view of the top plate-like member.

Figure 9 is a front end view of the bottom plate-like member of the door mechanism.

Figure 10 is a fragmentary plan view of the bottom plate-like member.

Figure 11 is a perspective view of one of the 15 wedging elements of the door mechanism.

Figure 12 is a plan view of a modified form of the top plate-like member of the door mechanism.

Figure 13 is a side view of the plate-like member shown in Figure 12.

Figure 14 is a plan view of a modified form of the bottom plate-like member of the door mechanism.

Figure 15 is a side view of the plate-like member illustrated in Figure 14.

Referring more particularly to the drawings, I indicates one of the hoppers of a railway car which may be conveniently formed by a plurality of sheets 2 and to the lower end of which is secured a door frame 3 provided with an opening through which lading within the car is adapted to discharge by gravity. The frame 3, which is of rectangular shape to conform with the discharge end of the hopper, is preferably formed in two cast metal sections, an upper section 4 and 30 a lower section 5.

The upper section is formed with a plurality of walls 6 for attachment to adjacent portions of the hopper sheets. At their lower ends, the side and inner end walls of the frame terminate in laterally projecting flanges 7 to which the lower section of the frame is secured as by rivets 8. The flanges 7 along the sides of the frame continue outwardly, as indicated at 9, beyond the front wall of the frame and the latter is integrally provided at its lower end with a forwardly projecting flange 10 which is integrally joined with the portions 9 of the side flanges.

The lower section 5 of the frame has substantially vertical side walls 11 and a substantially 50 vertical inner end wall 12. The side and end walls are formed at intervals with enlarged portions 13 which are apertured for receiving the connecting rivets 8 and each is also formed along its upper edge with a laterally extending rib 14 55

or the like which abuts against the under side of adjacent portions of the flanges 7 of the upper section of the frame. Projecting inwardly from the side and inner end walls of the lower section 5 of the frame are flanges 15 which, together with adjacent portions of the flanges 7 of the upper section of the frame, form channels or grooves for receiving the door mechanism to be herein-after described. Spaced below the flanges 15 at 10 the inner end of the frame and along one side thereof are auxiliary flanges 16 defining a second groove or channel for receiving a detachable boot or the like indicated in dot and dash lines at 17 in Figure 5.

15 The side walls 11 of the lower section of the frame which are coextensive with the flanges 7 and the continuations 9 thereof of the upper section of the frame are connected inwardly of their outer ends by a substantially horizontal 20 plate portion 18 which is preferably disposed in the plane of the inwardly extending flanges 15 and is formed at its forward end with a depending rigidifying portion 19.

25 The door mechanism which is slidably supported upon the flanges 15 of the frame includes an upper plate-like member 20 and a lower plate-like member 21. The upper plate-like member constitutes the door for closing the lading discharge opening of the frame and the lower plate-like member constitutes means for raising the door upwardly to cause it to occupy an elevated position when closed.

30 The upper plate-like member or door, as it will be hereinafter referred to, has a plurality of 35 depending portions 22 in the form of strips or bars which, while they may be formed integral with the door, are preferably formed as separate elements, being riveted to the under side thereof. Each of the bars or strips 22 extends 40 transversely of the door for practically its entire width and each is formed, preferably adjacent its ends, with projections 23, the under sides of which are beveled or inclined, as indicated at 24.

45 Secured to the upper side of the lower plate-like member 21 are strips or bars 25 which are preferably identical, in all respects, with the strips or bars 22. The strips 25, however, are secured to the lower plate-like member so that the projections 26 thereof extend rearwardly, while the strips 22 of the door are secured to the latter so that their projections extend forwardly.

50 The strips 22 and 25 are secured to their respective plate-like members in such positions that, as shown in Figures 1 and 2, they will be disposed in overlapping engagement when the plate members have been caused to assume their innermost positions. If, when in these positions, 55 the lower plate-like member is moved outwardly relatively to the door, the strips 22 and 25 will be moved from engagement with each other until finally the door moves downwardly away from the plane of the lading discharge opening and its strips engage the lower plate-like member and the strips of the latter engage the door, as 60 shown in Figure 3. With the parts in this position, it will be perceived that, should the lower plate-like member be moved inwardly relatively 65 to the door, the latter will be raised upwardly into its elevated position by coaction of the inclined surfaces of the projections 23 and 26 of the strips.

70 Adjacent its inner end, the door is provided 75 with a rigid shoulder or the like 27 which, after

the lower plate member 21 has been initially moved to enable the door to move downwardly away from the plane of the lading discharge opening, is adapted to be engaged by a rigid shoulder 28 on the lower plate member so that 5 continued movement of the latter will induce movement of the door toward open position. The shoulder 27 on the door may be conveniently formed by a strip of metal 29 secured to the under side of the door and the shoulder 28 may 10 be formed by the forward face of that one of the strips 25 which is secured adjacent the inner end of the lower plate member. Strip 29 is preferably of greater thickness than strips 22 and 25 so that, irrespective of whether the door moves 15 downwardly away from the plane of the lading discharge opening after the lower plate member has moved into the position indicated in Figure 3, shoulders 27 and 28 will engage each other. The lower plate member is, however, formed with 20 an elongated slot 30 into which the strip 29 is adapted to extend when the door moves downwardly. Due to shoulders 27 and 28 being brought into engagement after the lower plate-like member has been initially moved to permit 25 the door to move downwardly, it will be appreciated that continued movement of the lower plate member will result in causing the door to move toward open position.

To facilitate opening of the door mechanism, 30 the forward ends of the door and the lower plate member are, when the door is in its closed elevated position, disposed outwardly of the hopper within a lateral extension of the door frame. This extension of the frame is provided with 35 substantially vertical side walls 31 extending upwardly from the inner ends of the continuations 9 of the flanges 7 of the upper section and with a horizontal wall 32 formed integrally with and projecting outwardly from the upper portion of the front wall of the upper section of the frame. Pivotaly mounted upon the frame is a hood 33 which is adapted to span the space defined by the vertical side walls 31 and the front edge of the horizontal wall 32 and thus house the projecting portion of the door and lower plate member. The hood is formed with a front wall 34 which is normally adapted to extend downwardly into the path of opening movement of the door and lower plate member, whereby it is necessary to move the hood into an elevated position before the door mechanism may be actuated. To secure the hood in its normal housing position, it is provided with lugs 35 which are cooperable with lugs 36 formed on the frame for 40 receiving conventional car seals, not shown.

Pivotaly mounted on the frame extension is a rotatable member 37 for locking the door and the lower plate member in their innerpost positions. This rotatable member may be conveniently in the form of a cam, as clearly shown in Figure 6, and, to prevent withdrawal of the door, it is adapted to be disposed within an opening 38 formed in the latter, and, to prevent withdrawal of the lower plate member, it is 45 adapted to be disposed in overlapping relation to the front face of the strip 25 which is secured to the lower plate adjacent the forward end thereof. The rotatable locking member is also adapted to cooperate with the hood 33, as shown 50 in Figure 3, to support it in a position enabling operation of the door mechanism.

At their forward ends, the door and lower plate member are provided with means whereby they may be easily operated by suitable means, 55

such, for example, as a pry bar or lever 39 shown in dot and dash lines in Figures 2 and 3. The means on the door for cooperating with the pry bar may be advantageously formed as a casting 40 and the means on the lower plate member for cooperating with the bar is also preferably formed as a casting 41.

The casting 40 is provided with a plate portion 42 overlyingly secured, as by rivets, to the upper surface of the door on opposite sides of a notch or recess formed in the front edge of the door. Depending from the plate portion 42 is a rib 43 which extends in and conforms to the notch formed in the door. This rib preferably continues, as indicated at 44, along the front edge of the casting in overlapping relation with the forward edge of the door. The portion of the casting disposed above the notched portion of the door is offset upwardly, as indicated at 45, and it is formed with a elongated slot 46 bounded by a reinforcing bead 47.

The casting 41 is likewise provided with a plate portion 48 which is secured in overlapping relation to the upper face of the lower plate member on opposite sides of a notch or recess formed in the front edge thereof. It is also provided with a depending portion having vertical side walls 49 and an end wall 50 which respectively conform to the contour of the notch or recess in the lower plate member. At their forward ends, the side walls 49 of the depending portion are connected by a substantially horizontal wall 51 which, in addition to being spaced downwardly from the plate portion 48 of the casting, is spaced outwardly from the end wall 50 of the depending portion so as to define an elongated opening 52 of substantially the same size as the opening 46 in casting 40.

The openings 46 and 52 are so disposed that, when the door and lower plate member are in their innermost positions, they will register with one another to receive the removable pry bar 39. While the openings may be only sufficiently large to receive the pry bar, they are preferably made of the approximate shape and size illustrated in the drawings, so that, in the event a pry bar is not available, an operator may easily grasp the castings. Furthermore, while the openings are in registration, when the door mechanism is in closed position, their arrangement is preferably such that the pry bar, when first inserted therein, will be disposed in substantially a vertical position, as shown in Figure 2.

In the operation of the device, the parts being in the position illustrated in Figure 2, the hood 33 is manually raised and the locking member 37 then rotated so as to occupy a position for maintaining the hood in elevated position, as shown in Figure 3. The removable pry bar or lever 39 is then inserted in the openings 46 and 52 of the castings 40 and 41, respectively, the bar being so disposed that its major portion extends below the lower plate member. An outward pull on the lower end of the pry bar will cause the latter to fulcrum or pivot about the inner edge of the opening 46 in the casting 40 on the door and thus induce the lower plate member to move outwardly relatively to the door. This relative movement of the lower plate and door will continue until the shoulder 28 engages the shoulder 27, at which time the lower plate member will have assumed a position enabling the door to move downwardly away from the plane of the lading discharge opening and thus break the adhesion between the door and lading. When the

shoulders 27 and 28 engage each other, as shown in Figure 3, continued outward pull upon the pry bar or lever will result in outward movement of both the lower plate member and the door until the strip 53 secured to the under side of the door 5 adjacent the inner edge thereof engages the inner edge of the horizontal plate portion 18. When this occurs, the door will be in the dotted line position illustrated in Figure 4. While the door may be permitted to remain in this position 10 while the lading discharges from the car, it is preferred that it be pulled out by hand further until it occupies the full line position shown in Figure 4. During this last increment of movement of the door independently of the lower plate member, the door is raised upwardly by coaction of the inclined surfaces of strips 22 and 25. In this manner, the space between the flange or plate 10 of the upper section of the door frame and the plate portion 18 of the lower section is closed by the door mechanism, when the latter is in open position, and lading, such as cement and the like, is effectively prevented from being puffed or blown out through this space. 25

It will be observed that, when the pry bar is first operated to effect relative movement of the door and lower plate member, it functions as a lever but that, when it is operated after relative movement between the door and lower plate has 30 been arrested by shoulders 27 and 28, it merely functions as a handle or door extension.

In the closing operation of the door mechanism, force may be applied to both the door and the lower plate member to cause them to move 35 simultaneously into closed position or force may be applied to either one of them, in which event the other will also be caused to move toward closed position. If a closing force is applied to the door alone, it will move inwardly relatively 40 to the lower plate member until shoulders 27 and 28 engage, at which time continued inward movement of the door will result in corresponding movement of the lower plate member. The door and lower plate member will then eventually 45 assume the positions shown in Figure 3 and it only remains for the lower plate member to be moved inwardly relatively to the door to cause the latter to assume its elevated position. In the event a closing force is applied to the lower 50 plate member alone, it will move inwardly relatively to the door until the forward edge of strip 29 is engaged by the inner face of an adjacent strip 25, at which time continued inward movement of the lower plate member will induce corresponding movement of the door. After the lower plate member has been moved inwardly as far as possible, it is then only necessary to push the door inwardly a slight distance. 55

After the door and lower plate member have 60 assumed their innermost positions, the locking member 37 is freed from engagement with the hood 33 and rotated into locking association with the door and plate member. The hood is then permitted to move downwardly and the car 65 seals applied.

While the strips 22 and 25, which are respectively secured to the door and bottom plate member adjacent their forward ends, will suffice to elevate the front portion of the door, this result 70 may be additionally assured by providing the casting 41 with a pair of upwardly extending ribs 54, the inner portions of which are inclined, as at 55, for cooperation with the forward end of the casting 40 which may also be inclined as 75

indicated at 56. To prevent lading which might possibly seep into the space between the door and lower plate member from interfering with the successful operation of the door mechanism, 5 the plate member is preferably provided with a plurality of elongated openings 21a through which lading collecting on the plate may escape.

Instead of providing the door and lower plate member with the strips 22 and 25 for raising the 10 door upwardly and supporting it in an elevated position, they may be integrally formed with embossments or offsets, as illustrated in Figures 12 to 15, inclusive. In Figures 12 and 13, a door 57 is shown provided with a plurality of embossments 15 58 and, in Figures 14 and 15, a lower plate member 59 is shown provided with a plurality of embossments 60 preferably identical with the embossments 57. The embossments are each provided with horizontal outer surfaces 61 and 20 with inclined sides 62 and those in the door are so arranged with respect to those in the lower plate member that, when these parts are in their innermost positions, the horizontal surfaces of the embossments will be disposed in overlapping 25 engagement whereby the door will be supported in an elevated position. It will be apparent that, when the lower plate member is moved outwardly relatively to the door, the embossments will be moved from engagement with each other and thus enable the door to move downwardly and that, when the parts are in this position, if the lower plate member is moved inwardly relatively to the door, the latter will be raised upwardly by coaction of the adjacent inclined walls of 30 neighboring embossments.

Like door 20, door 57 is provided with a depending strip 63 affording a shoulder cooperating with a portion of the lower plate member whereby, after the latter has been initially moved independently of the door, continued movement thereof will result in moving the door toward open position. Moreover, door 57 is provided with an opening 64 and plate member 59 is provided with a strip 65 for cooperating with the rotatable locking member in the same manner as the respectively corresponding parts of the door 20 and the lower plate member 21. The forward edges of door 57 and plate member 59 are also preferably notched or recessed so as to respectively receive parts similar to castings 40 and 41.

From the foregoing, it will be perceived that simple, reliable and rugged means has been devised for supporting the door in an elevated position, so as to enable it to move downwardly away 55 from the plane of the lading discharge opening before assuming open position and thus break the adhesion between the door and the lading supported thereby.

What I claim is:

- 60 1. A railway car having a floor provided with a door frame defining a lading discharge opening, a sliding door mounted on the frame for closing said opening, and means interposed between the door and frame for supporting the door in an elevated position when the latter is closed, said means being initially movable independently of the door to enable the latter to move downwardly away from the plane of the lading discharge opening and said door and means respectively having portions rigid therewith adapted to engage each other upon completion of said initial movement of said means whereby continued movement of the latter causes the door to move toward open position.
- 70 2. A railway car having a floor provided with

a door frame defining a lading discharge opening, a sliding door mounted on the frame for closing said opening, and movable means interposed between the door and frame for raising the door upwardly to cause it to occupy an elevated position when the latter is closed, said door and means respectively having rigid shouldered portions disposed in spaced relation when the door is in closed elevated position, said means being initially movable independently of the door to enable the latter to move downwardly and to bring said shouldered portions into engagement and being thereafter movable to slide the door toward open position.

3. A railway car having a floor provided with a door frame defining a lading discharge opening, a door slidably mounted on the frame for closing said opening, and wedge means movably interposed between the frame and door, said means being slidable with respect to the door and having inclined portions engageable with the door for raising the latter upwardly toward the plane of the lading discharge opening to cause it to occupy an elevated position when closed.

4. A railway car having a floor provided with a door frame defining a lading discharge opening, a sliding door mounted on the frame for closing said opening, and means slidably mounted upon the frame rigidly provided with an upwardly facing inclined portion cooperable with the door for raising the latter upwardly toward the plane of the lading discharge opening to cause the door to occupy an elevated position when closed.

5. A railway car having a floor provided with a door frame defining a lading discharge opening, a sliding door mounted on the frame for closing said opening, and means slidably mounted upon the frame for supporting the door in an elevated position when the latter is closed, said door and means having inclined faces cooperable with each other for raising the door into said elevated position.

6. A railway car having a floor provided with a door frame defining a lading discharge opening, a sliding door mounted on the frame for closing said opening, and means movably interposed between the door and frame adapted to slidably engage said depending portions for raising the door upwardly toward the plane of the lading discharge opening to cause it to occupy an elevated position when closed.

7. A railway car having a floor provided with a door frame defining a lading discharge opening, a sliding door mounted on the frame for closing said opening, said door having depending portions extending at an angle to the direction of sliding movement thereof, and slidably means interposed between the door and frame having wedging engagement with said depending portions for raising the door upwardly toward the plane of the lading discharge opening to cause the door to occupy an elevated position when closed.

8. A railway car having a floor provided with a door frame defining a lading discharge opening, means slidably mounted upon the frame constituting a door for closing said opening, said means having one or more transversely extending depending portions, and means slidably interposed between said means and frame having one or more upwardly extending portions for respectively cooperating with said depending portions to support the door in an elevated position when closed, the portions of at least one of said means

having inclined faces cooperable with the portions of the other of said means for raising the door into said elevated position.

9. A railway car having a floor provided with a door frame defining a lading discharge opening, and two plate-like members slidably mounted on the frame, one of said members constituting a door for closing said opening and being provided with depending portions, the other of said members having means cooperable with said depending portions for raising the door upwardly toward the plane of the lading discharge opening to cause it to occupy an elevated position when closed.

10. A railway car having a floor provided with a door frame defining a lading discharge opening, and upper and lower plate-like members slidably mounted on the frame, said upper member constituting a door for closing said opening and being provided with depending portions and said lower member having a plurality of means respectively cooperable with said depending portions for moving the door upwardly to cause it to occupy an elevated position when closed and for actuating the door to move it toward open position.

11. A railway car having a floor provided with a door frame defining a lading discharge opening, and upper and lower plate-like members slidably mounted on the frame, said upper member constituting a door for closing said opening and said lower member constituting means for supporting the door in an elevated position, said members respectively having offset portions cooperable with each other to raise the door into said elevated position.

12. A railway car having a floor provided with a door frame defining a lading discharge opening, a sliding door mounted on the frame for closing said opening, and slidable means carried by the frame for moving the door upwardly to cause it to occupy an elevated position when closed, said means being slidable with respect to the door a limited extent to enable it to move downwardly

away from the plane of the lading discharge opening and being provided with a portion engageable with the door after the latter has moved downwardly for causing the door to move with said means to open position, said door and means having spaced portions cooperable with a removable lever adapted to move said means relatively to the door and to thereafter move said means and door together.

13. A railway car having a floor provided with a door frame defining a lading discharge opening, a sliding door mounted on the frame for closing said opening, and means carried by the frame for moving the door upwardly to cause it to occupy an elevated position when closed, said means being slidable with respect to the door a limited extent to enable it to move downwardly away from the plane of the lading discharge opening, said door and means respectively having apertures for receiving a removable bar adapted to serve as a lever for moving said means with respect to the door and also adapted to serve as a handle for moving said means and door together.

14. A railway car having a floor provided with a door frame defining a lading discharge opening, a sliding door mounted on the frame for closing said opening, and means interposed between the door and frame for moving the door upwardly to cause it to occupy an elevated position when closed, said means being initially movable independently of the door to enable the latter to move downwardly away from the plane of the lading discharge opening and being provided with a portion engageable with the door upon completion of said initial movement whereby continued movement thereof causes the door to move toward open position, said door and means respectively having portions cooperable with a removable bar adapted to first move said means independently of the door and to thereafter move said door and means together.

CYRUS HANKINS.
